TOY STEAM SHOVEL OR SIMILAR ARTICLE

Robert K. Richardson, P.O. Box 1121,
Walla Walla, Wash. 99362

Filed Sept. 30, 1968, Ser. No. 13,787

Term of patent 14 years

Int. Cl. D21—02

U.S. Cl. D34—15

FIG. 1

FIG. 2

FIG. 3

FIG. 4

FIGURE 1 is a front isometric view of a toy steam shovel or similar article embodying my new design.

FIGURE 2 is a side fragmentary view with the bucket opened.

FIGURE 3 is a side fragmentary view with the bucket retracted.

FIGURE 4 is a side fragmentary view with the bucket extended.

I claim:

The ornamental design for a toy steam shovel or similar article, substantially as shown.
